[57] CLAIM

The ornamental design for an aerosol container, as
shown and described.

DESCRIPTION

FIG. 1 is a perspective view of an aerosol container
showing my new design;

FIG. 2 is a front elevational view thereof, the rear being
identical;

FIG. 3 is a right side elevational view thereof, the oppo-
site side being identical;

FIG. 4 is a top plan view thereof;

FIG. 5 is a bottom plan view thereof; and

FIG. 6 is a perspective view thereof in the position for
use.
